UNITED STATES PATENT OFFICE.

LEONARD C. HOLLINGWORTH, OF PROVIDENCE, RHODE ISLAND.

SELVAGE-GUIDE FOR CLOTH-SHEARING MACHINES.

SPECIFICATION forming part of Letters Patent No. 598,264, dated February 1, 1898.

Application filed July 9, 1897. Serial No. 643,960. (No model.)

To all whom it may concern:

Be it known that I, LEONARD C. HOLLINGWORTH, of Providence, in the county of Providence and State of Rhode Island, have invented a new and useful Improvement in Selvage-Guides for Cloth-Shearing Machines; and I hereby declare that the following is a full, clear, and exact description of the same, reference being had to the accompanying drawings, forming part of this specification.

This invention has reference to an improvement in the class of cloth-shearing machines in which a series of vertical parallel sections operated by a sliding bar with a cam-slot formed therein are used, as is shown and described in United States Patent No. 207,091, of August 13, 1878, to Amasa Woolson, for improvement in rests for cloth-shearing machines. In these machines the rest is operated to adjust itself to the width of the cloth to be sheared by the serrated feelers over which the selvage passes. As the selvage is usually more or less wrinkled, it is found in practice that the selvage will pass over the serrated feelers for some distance without affecting the feelers.

The object of this invention is to hold the cloth at all times against the serrated feelers and insure the automatic adjustment of the rest; and to this end the invention consists in providing the sliding bar of the rest with an arm extending longitudinally above the sliding bar, provided at its end with a bracket on which a selvage-guide is supported, whereby the cloth is held in contact with the serrated feelers, as will be more fully set forth hereinafter.

Figure 1 is a front view of the automatically-adjustable rest, showing the same provided with the improved selvage-guide. Fig. 2 is a transverse sectional view of the rest, showing the selvage-guide. Fig. 3 is a sectional view of the end of the selvage-guide. Fig. 4 is a top view of a modified form of the selvage-guide. Fig. 5 is a top view, on an enlarged scale, of the selvage-guide and the arm supporting the same.

In the drawings, A A indicate the sliding sections of the rest, which are controlled by the slot B, formed in the slide C.

D is the backing or support; E, a bracket secured to the slide C and forming the piv-

otal support for the serrated feeler G and the cam H; F, a double ratchet-bar in connection with the feeler G and the cam H.

The drawings show only one end of the rest; but in practice both ends of the cloth-rest of a shearing-machine are constructed in the same way, with the positions of the parts reversed.

The double ratchet-bars F, on opposite ends, are operated to reciprocate, and when one or the other side of the cams H engage with the ratchet-bars F the slide C is moved, and this operates the sections A, as is more fully described in the Patent No. 207,091 to A. Woolson, before referred to.

To the slide C, or to an extension C' of the slide, I secure the arm K, the base K' of which is provided with two elongated holes, so that it can be adjustably secured to the slide C or the extension C'. The arm K is bent or offset, so as to extend above the cloth-guide and permit the cloth to pass under the arm. To the free end of the arm K the bracket K³ is secured, and this bracket K³ may be bent to form the guide-finger K⁴, the end of which is bent upward to insure the entrance of the cloth at all times under the guide. In the preferred form I use a separate guide-finger K⁵, having the conical shoulder K⁶ and the roller or loose collar K⁷, and secure the same to the bracket K³ by the nut K⁸, which nut may be secured against getting loose by vibration in the usual manner. The bracket K³ is secured to the arm K by the nut K⁹ or a screw tapped into the arm and provided with a head, so that the bracket may be adjusted to bring the guide-finger or the roller K⁷ in contact with cloth of varying thickness and hold the cloth, the selvage, or the "list," as the selvage of woolen cloth is termed, in contact with the feelers G at the opposite ends of the rest, and thereby secure the prompt operation of the automatic rest and the clean shearing of the cloth through the whole length of the cloth.

Having thus described my invention, I claim as new and desire to secure by Letters Patent—

1. In a cloth-shearing machine, the combination with the cloth-rest, the sliding end sections of the rest, the slide operating the end sections, and the feelers controlling the position of the slides, of guide-fingers sup-

ported on the slides, said fingers bearing on the cloth at the point of contact with the feelers, whereby the prompt adjustment of the cloth-rest is secured, as described.

- 5 2. In combination with the cloth-rest, the sliding end sections, the slide operating the end sections, and the feelers controlling the position of the slides, of an arm adjustably secured to the slide operating the end sections
10 at a point beyond the possible passage of the cloth, and a finger-bracket supported by the arm; said finger bearing on the cloth at the point of contact with the feelers, as described.
3. The combination with the slides and the

feelers of a rest for cloth-shearing machines 15 of the kind described, of the arm K, the bracket K³ adjustably secured to the arm K, the bent finger K⁵, the roller K⁷, and means, substantially as described, for securing the finger to the bracket, whereby the rollers may 20 be adjusted to bear on the cloth in its passage over the feelers, as described.

In witness whereof I have hereunto set my hand.

LEONARD C. HOLLINGWORTH.
